UNITED STATES PATENT OFFICE.

ROBERT H. CAMPBELL, OF CHICAGO, ILLINOIS.

DISPENSING-CONTAINER.

1,296,045.

Specification of Letters Patent.

Patented Mar. 4, 1919.

Application filed November 20, 1916. Serial No. 132,465.

To all whom it may concern:

Be it known that I, ROBERT H. CAMPBELL, a citizen of the United States, and resident of Chicago, in the county of Cook and State 5 of Illinois, have invented a new and useful Dispensing-Container, of which the following is a specification.

This invention relates to dispensing containers and relates particularly to spouts for 10 such containers, as for oil cans, grease guns, funnels, hoppers and the like.

The object of the invention is to provide 15 a spout for a container which may be conveniently inserted into places which would be inaccessible with containers having usual forms of spouts.

Stated broadly, my invention consists in the provision of a flexible spout for dispensing containers, which is substantially non- 20 resilient and which is of sufficient stiffness so that it will retain different shapes into which it is bent. Specifically, my improved container spout is made of what is generally known as flexible metal tubing.

25 My invention also comprises the various other features and details of construction hereinafter described and claimed.

In the accompanying drawings, in which my invention is fully illustrated,

30 Figure 1 is a side view of a container spout embodying my invention.

Fig. 2 is an enlarged, longitudinal sectional view thereof.

Fig. 3 is a view similar to Fig. 2 showing 35 modified means for connecting the spout to the container; and

Figs. 4, 5 and 6 illustrate the application of my improved spout to different forms of containers.

40 Referring now particularly to Figs. 1 and 2 of the drawings, in which I have shown what I now consider to be the preferable form of spout embodying my invention, 1 designates a section of flexible metal tubing 45 of any desired length, secured to the end of which designed to be connected to the container is a nipple 2 and secured to the opposite or discharge end of which is a nozzle 3. As shown, said nipple 2 and nozzle 3 50 are connected to the ends of the section 1 of metal tubing by means of solder, this being effected in a simple manner by forming sleeves 4 and 5 on said nipple and nozzle, respectively, into which the ends of the section 1 of flexible metal tubing are inserted and soldered. The nipple 2 is adapted to

be screwed into a nut indicated in dotted lines at 6, Fig. 1, secured in a hole or opening formed in the container wall, indicated in dotted lines at 7.

Obviously, if desired, this arrangement 60 may be reversed, the nipple being secured to the container and the nut to the spout.

This modification is shown in Fig. 3 of the drawings, in which 1' designates the 65 section of flexible metal tubing forming the spout, and 8 a nut secured to the end thereof adapted to be connected to the container, not shown.

I do not desire, however, to limit myself 70 to the particular means shown for connecting my improved spout to the container, as means other than those shown in Figs. 1, 2 and 3 will readily suggest themselves to persons skilled in the art. Also, if desired, 75 my invention contemplates securing said spout to the container by means of a permanent connection, which can be conveniently made by soldering the end of the section 1 of flexible metal tubing into a sleeve 80 or bushing permanently secured to the wall of the container, as best shown in Fig. 5, presently to be described.

To provide for conveniently inserting the discharge end of the nozzle 3 into oil holes 85 and other small holes, said nozzle is preferably tapered toward its outer end. Obviously, the shape and size of said nozzle admits of a wide range of variation to meet various conditions, and I do not, therefore, 90 desire to limit myself in this respect.

For purposes of concrete illustration, I have, in Figs. 4, 5 and 6, of the drawings, shown three different applications of my improved flexible spout, which I will now describe.

In Fig. 4 of the drawings, in which I have shown a spout of my invention as applied in use to a well known form of oil can, A designates the oil can proper, which 100 may be of any usual or approved construction, a a nut secured in the discharge opening of said container, 1² the section of metal tubing forming the spout of said oil can, 2² the nipple secured to the inner end of said 105 flexible tube 1², which is threaded into the nut a secured in the oil can A, and 3² the nozzle secured to the outer or discharge end of the flexible section 1² of said spout.

In Fig. 5, in which I have shown the 110 spout of my invention as applied in use to a funnel, B designates the funnel, which may

be of any usual or approved construction, 1³ the section of flexible tubing forming the discharge spout from said funnel, the inner end of said flexible tube 1³ being permanently soldered into a sleeve *b* formed at the lower end of the funnel *B*, and 3³ is the nozzle secured to the outer end of the flexible section 1³ of said spout.

In Fig. 6, in which I have shown a flexible spout of my invention applied in use to what may be called a carrying can, which is adapted either for carrying liquids or granular solids, as sugar, small grains and the like, *C* designates the can proper secured in 15 a discharge opening adjacent to the upper end of which is a nipple *c*, 1⁴ is the section of flexible tubing forming the body portion of my improved flexible spout, 2⁴ is a nut secured to the inner end of said section 1⁴ of 20 flexible tubing adapted for engagement with the nipple *c* on the can *C*, and 3⁴ is the nozzle secured to the outer or discharge end of said flexible tube section 1⁴.

The number of different uses to which my 25 improved spout may be applied might be increased almost indefinitely, but, in view of the foregoing disclosure and illustrations,

such uses and adaptations can readily be made by skilled mechanics, and it is, therefore, believed that additional illustration of 30 specific applications of my improved spout is unnecessary.

I claim:—

1. A distributing container, comprising a receptacle, and a spout therefor, said spout 35 being flexible under pressure without appreciable distortion in cross section, substantially non-resilient, and sufficiently rigid to retain its shape unsupported, substantially as described.

2. A spout for a distributing container, which is flexible under pressure without appreciable distortion in cross section, substantially non-resilient, and of sufficient rigidity to retain its shape unsupported, substantially as described.

In testimony, that I claim the foregoing as my invention, I affix my signature in the presence of two subscribing witnesses this 17 day of Nov., 1916.

ROBERT H. CAMPBELL.
